UNITED STATES PATENT OFFICE.

DARCY A. YOUNG, OF MILFORD, MASSACHUSETTS, ASSIGNOR TO AMERICAN WRINGER COMPANY, OF WOONSOCKET, RHODE ISLAND, A CORPORATION OF RHODE ISLAND.

WRINGER.

1,329,570.

Specification of Letters Patent.

Patented Feb. 3, 1920.

Application filed April 28, 1919. Serial No. 293,283.

To all whom it may concern:

Be it known that I, DARCY A. YOUNG, a citizen of the United States, residing at Milford, in the county of Worcester and State of Massachusetts, have invented a new and useful Improvement in Wringers, of which the following is a specification.

This invention relates to certain new and useful improvements in a wringer and more particularly to attachments for the wringer frame to increase the efficiency and safety of the machine.

The principal object of the invention is to provide a wringer with a safety device for relieving the wringer rolls of pressure in an emergency, and a further object is to mount an improved guide board on the wooden frame of the wringer.

Other objects will appear as the description progresses, and those features on which protection is desired will be defined in the appended claims.

In the drawings:

Figure 1 is a front elevation of a wringer embodying the present invention.

Fig. 2 is a top plan view and Fig. 3 is an end elevation thereof.

Fig. 4 is a fragmental view depicting the safety device in vertical section.

Fig. 5 is a top plan view of the safety device operative, and

Fig. 6 is a lengthwise section therethrough on line 6-6 of Fig. 5.

More specifically referring to the drawings, the numerals 1 designate the end uprights of the wooden wringer frame, 2 the squeeze rolls which have their end trunnions journaled in bearings 3 disposed in the vertical guideways 4 of the uprights, and 5 the intergearing between the rolls for transmitting motion from one to the other as imparted thereto by a crank handle 6 or other motive power not shown.

Arranged on each side of the wringer frame is a guide board 7 preferably cast from aluminum with terminal right angular vertical brackets 8 to embrace the inside and front faces of the uprights 1. The brackets also define side walls for the guide board 50 to prevent the clothes from riding off the ends of the rolls. Braces 9 underlie the guide boards and not only serve as a reinforcement to the frame but also to said guide boards.

Coiled springs 10 are seated on the upper

roll bearings 3 and housed within the guideways 4 and on each spring is a cap bearing 11. The upper ends of the frame uprights carry fittings 12 having inturned lips 13 that overhang the cap bearings 11 and are designed to have the outer ends of a pressure releasing or relieving bar 14 engage there beneath. This bar comprises jointed sections for breaking upwardly which breaking action will withdraw the outer ends from beneath lips 13 and thus release the springs to relieve the rolls from the pressure.

To hold this sectional folding bar in extended position, a locking lever 15 is pivoted on the inner end of one section to swing over the adjacent end of the companion bar section and engage a keeper lug 16.

The locking lever is equipped with a pair of oppositely extending handles 17, one on each side of the breakable bar and broadened to provide a relatively large striking surface. Threaded through the outer ends of the bar are screws 18 adjustable by the head wings 19 to vary their pressure on the cap bearings and springs.

In practice should the clothing bunch between the rolls or an attendant have his hand drawn in therebetween, it is only necessary to strike or push against either handle 17 which will swing the lock lever clear of its keeper and permit the bar breaking upwardly under the influence of the springs which breaking withdraws the bar terminals from beneath the lips 12. Thus, the springs are free to expand and thereby relieve the upper roll from pressure.

The safety pressure relieving device is simple and efficient being applicable to any form of wringer, either manually or mechanically operated. When the safety device is operated it removes all pressure from the springs and rolls and when inoperative it functions as a brace for the wringer frame.

Having thus described my invention, what I claim as new and desire to secure by Letters Patent is—

1. In combination with a wringer frame and lips on the upper end of the frame, a pressure bar composed of sections, the inner ends of which abut each other, the outer ends of the sections being engageable beneath said lips, means to hingedly connect said inner ends of the sections, a keeper lug

formed on the upper face of one section, a horizontally disposed lock member pivoted to move in a horizontal plane and borne by the upper face of the other section and having a pair of oppositely disposed spaced handles arranged, one on and along each side of the frame, and a catch centrally arranged in the space between the handles and having a downwardly facing part receiving and operating over the keeper lug.

2. In combination with a wringer frame and lips on the upper end of the frame, a pressure bar composed of sections, the inner ends of which abut each other, the outer ends of the sections being engageable beneath said lips, means to hingeably connect said inner ends of the sections, a keeper lug formed on the upper face of one section, a horizontally disposed lock member pivoted to move in a horizontal plane and borne by the upper face of the other section, said

member having a downwardly facing catch extending outwardly from an end thereof and engageable over the keeper lug, a handle extending outwardly from said end of the member and arranged alongside the keeper and spaced therefrom, and a second handle extending outwardly from the opposite end of the member in a direction opposite to the first handle and substantially parallel thereto, the handles extending longitudinally along the frame sides, and having parts engaged with the respective opposite sides of the frame so as to limit swinging of the lock in both directions.

In testimony whereof I have signed my name to this specification in the presence of two subscribing witnesses.

DARCY A. YOUNG.
